(57) **CLAIM**

The ornamental design for a utensil rest, as shown and described.

DESCRIPTION

FIG. 1 is a perspective view of a utensil rest, showing my new design;

FIG. 2 is a front elevation view of the utensil rest;

FIG. 3 is a rear elevation view of the utensil rest;

FIG. 4 is a left side elevation view of the utensil rest;

FIG. 5 is a right side elevation view of the utensil rest;

FIG. 6 is a top plan view of the utensil rest; and,

FIG. 7 is a bottom plan view of the utensil rest.

The broken lines in the figures illustrate the portions of the design that form no part of the claimed design.
